Eli. Kendall's Boarding Machine

8911 X Sallet's Patent

The Schedule is referred to in these Sallet's Patent and making part of the same containing a description in the words of the said Eli Kendall him self of his improvement in the mode of Boarding or softening skins by making called "The Boarding Machine for boarding or softening skins."

To all persons to whom these Presents shall come
Eli Kendall of Ashby in the County of Middlesex and Commonwealth of Massachusetts Mechanist sends greeting. Be it known that the said Eli Kendall have invented contrivances made and applied to use a new and useful improvement in the mode of boarding or softening skins by machinery called the "Boarding Machine for boarding or softening skins." This improvement in boarding or softening skins consists in the following particulars. By the old mode and the one in fact that is generally in use, and the only one known to me the said Eli, saving the machine by me invented - in order to soften skins a layer of cork is fastened to a piece of board, on the other side of the board a leather strap is fastened; into which the hand is inserted and the hand is then rubbed with the cork side next to the skin over the skin back and forth until the skin becomes sufficiently softened for use, this is a slow and laborious process. In the machine which I have invented the same work is done in the following method which will be more fully understood by a reference to the model or drawing accompanying this description.
The drawing represents a table B.B, whose top is six feet square according to the scale adopted in this drawing - supported by legs three feet high, up on each side of the table B.B, are grooves in which the slides C.C, travel
The slides C.C, support a frame A.A, which is loaded with the property and the under surface of the frame is covered with India rubber. This frame is attached to the slides C.C, by a double vein hinge H, at each lower corner and is moved up the inclined plane C.C, upon rollers B.B, by means of the connecting crank H.H, which is attached to the slides by the frame C.C, the upright ends of which pass through the grooves and are mortised into the

St. Louis, Mo. The mode or process of hoarding or softening skins by this machine was following: viz: a skin is doubled with its polished surface inwards (and is held upon the table while the rubber frame moves up the inclined plane upon its rollers as far as $\frac{1}{2}$ in. where it rolls off and falls upon the skin (and is then drawn back toward to the end of the inclined plane where the motion is again repeated. By this process the skin whether morocco, kid, calf, or any other skin is speedily softened. The present machine will do the work of the men in the old way (and may be worked either by water power, by steam, by horse power or by hand), in all of which ways its use has been contemplated by the said Eli. In testimony that the above is a true specification of my said improvement as above described, I have hereunto set my hand and seal this fourth day of October (A.D.) 1835.
